UNITED STATES PATENT OFFICE.

EUGENE O. FOX, OF CLEVELAND, OHIO, ASSIGNOR TO BENJAMIN F. KLEIN, OF CLEVELAND, OHIO.

DESIGN FOR A DOUBLE-ENDED HOLLOW LOOP.

48,366.

Specification for Design.

Patented Jan. 4, 1916.

Application filed August 6, 1915. Serial No. 44,128. Term of patent 3½ years.

To all whom it may concern:

Be it known that I, EUGENE O. Fox, a citizen of the United States, residing at Cleveland, in the county of Cuyahoga and State of Ohio, have invented a new, original, and ornamental Design for a Double-Ended Hollow Loop, of which the following is a specification, reference being had to the accompanying drawing, forming part thereof.

Figure 1 is a front view of a double ended hollow loop, showing my new design. Fig. 2 is a side view of the same.

I claim:

The ornamental design for a double ended hollow loop, as shown.

EUGENE O. FOX.
